US00D698785S

(12) **United States Design Patent**
Canizares et al.

(10) **Patent No.:** US D698,785 S
(45) **Date of Patent:** ** Feb. 4, 2014

(54) **ELECTRONIC TABLET DEVICE**

(75) Inventors: **Wilfrido Loor Canizares**, San Francisco, CA (US); **Hoang M. Nguyen**, San Francisco, CA (US); **Christopher Green**, San Francisco, CA (US)

(73) Assignee: **Amazon Technologies, Inc.**, Reno, NV (US)

(**) Term: **14 Years**

(21) Appl. No.: **29/430,018**

(22) Filed: **Aug. 20, 2012**

(51) LOC (10) Cl. 14-02
(52) U.S. Cl. USPC .....

(57) **CLAIM**

The ornamental design for an electronic tablet device, as shown and described.

DESCRIPTION

FIG. 1 is a perspective view of an electronic tablet device showing the new design;

FIG. 2 is another perspective view of the electronic tablet device of FIG. 1;

FIG. 3 is a front elevation view of the electronic tablet device of FIG. 1;

FIG. 4 is a back elevation view of the electronic tablet device of FIG. 1;

FIG. 5 is a top plan view of the electronic tablet device of FIG. 1;

FIG. 6 is a bottom plan view of the electronic tablet device of FIG. 1;

FIG. 7 is a left-side elevation view of the electronic tablet device of FIG. 1; and,

FIG. 8 is a right-side elevation view of the electronic tablet device of FIG. 1.

The broken lines shown in the drawings represent portions of the electronic tablet device which form no part of the claimed design.

The electronic tablet device is used for viewing and/or reading content.

1 Claim, 6 Drawing Sheets
